BURNER FOR LIQUID FUELS WITH COMBUSTION AIR UNDER ATMOSPHERIC PRESSURE FOR INDUSTRIAL AND DOMESTIC PURPOSES

Mario Nava, Macclesfield, England

Application October 21, 1949, Serial No. 122,768

3 Claims. (Cl. 158—91)

1

This invention has for its object, a burner for liquid fuels with combustion air under atmospheric pressure for industrial and domestic purposes.

The main object of the invention is the realisation of a burner for liquid fuels such for instance as naphtha or similar fuels to realize a notable economy of combustion, while at the same time ensuring maximum efficiency.

These objects are achieved by the burner described herein which is distinguished in the main by the fact that it comprises a basin fitted with at least one annular channel, into which enters the fuel duct, which annular channel is limited outside by a flat annular section extended against the inside wall of the body of the basin, which is enclosed by a movable cap fitted ringwise with flame splitting fissures across which can pass the combustion air, the said basin being arranged to run axially by means of suitable guides in a substantially cylindrical cover disposing the said basin in such a way as to define between the outside wall of the latter and the internal wall of the said cover, an intervening space for the passage of the combustion air, there being moreover provided suitable means to obtain an axial displacement of the basin in relation to the cylindrical cover, to permit of regulating the flame.

Since the burner made in this way would be noisy, in order to avoid such inconvenience, there is provided an additional cap made essentially like a glass placed upside down, with a hole in the bottom and of such dimensions as to form substantially a continuity of the cylindrical body of the basin on which it is applied, the said additional cap being provided with a series of openings arranged in its annular wall.

In a practical form of construction of the burner, the basin is made in the form of a cylindrical body with bottom provided with a central inlet for the passage of the supplementary combustion air and limited by a small channel into which the liquid fuel flows, introduced by a tube for the purpose, which small channel is limited externally by annular step to establish a constant position of the flame splitting cap, there being provided on the top of the cylindrical wall of the said basin, suitable means for the application of the silencing cap.

The basin is, moreover, provided externally with guides for its axial motion, also with coupled levers for raising or lowering it to adjust the flame.

The invention will now be described more precisely in relation to a form of execution, given as

2

an example, illustrated in the attached drawing, in which:

Fig. 1 is a longitudinal section of the burner, on a reduced scale.

Fig. 2 is a top plan view of the mechanism shown in Fig. 1; and

Fig. 3 represents a front elevation of Fig. 1.

With regard to the attached drawing, 1 indicates the basin, 2 the central collar for the passage of the air, 3 the liquid fuel supply duct, 4 shows the flame splitting cap, which limits tube 3 delivering the fuel and is fixed in its position by means of a stop 5 concentric to the geometric axis of the basin.

15 The basin 1 is fitted on its outside wall with guiding means 6, directed parallel to its longitudinal axis, engaged with corresponding guiding means 7, presented by the inside wall of a cover 8 or burner head, formed by a trunk-cylindrical body of such diameter as to form an intervening space 9 between its inside wall and the outside wall of the basin. Head 8 is provided with horizontal lips 10 which rest on supports 11, carried by plate 12, which is fitted with

20 a hole 12a, to establish the continuity between the inside of the oven and the annular intervening space 9.

25 Plate 12 acts as a lid and at the same time forms a means of application to the oven or other place where the burner is applied.

30 To support the basin 1, there is provided a clamp 13, which with arms 14, carries the basin 1 and at the same time serves to make it move axially, for the purpose of regulating the flame. For this purpose, there is fastened on clamp 13 at 13a, one end 15' of a lever 15, in its turn fastened at point 16 to an upright 17 made solid by means of bolts 18 or otherwise with an arm 19 carried by cover 8, which lever is fastened

35 at its other end 15" to a threaded stem 21 by means of a bolt 20. The threaded stem 21 can be made to move axially cooperating with a button 22 provided with a threaded hole 22', in which the said stem 21 can move, but not revolve on itself.

40 To obtain this end, there is provided a collar 23, within which the extension 22' of the said button can rotate freely, which extension has an annular groove 24, in which enters a fixed bolt 25 which prevents the button 22 becoming displaced axially, compelling instead threaded stem 21 to move axially.

45 For silencing the burner, there is provided an additional cap 26 in the form of a glass upside down, which with the opening 27, rests on a cor-

responding annular step on the basin 1 and finishes with the end 28 tapering and limiting a hole 29, while on the lateral wall it shows a series of windows 30 for ventilation purposes.

Having given this description, the working of the burner may be summarized in a few words.

The liquid fuel coming from duct 3 enters the annular intervening space of the basin 1, defined by stop 5 for holding cap 4 in a constant position and by the outside wall of opening 2.

The said fuel is ignited by any means whatsoever, thereupon applying again the additional cap 26.

In order to regulate the flame, it is necessary to manipulate the button 22. By turning this button in one direction or another, one effects a displacement of the lever 15 with its respective clamp 13 and with it, therefore, an axial movement of the basin 1, the latter resting on arms 14 of clamp 13.

Among the numerous advantages of the burner, as per the invention, are those relative to the elimination of a fan, a compressor and the use of electric current.

The burner, according to the invention may of course be varied according to the use to which it is to be put, namely, whether it is to be used for industrial or domestic purposes, without, however, departing from the spirit and scope of the invention as set forth in the claims appended hereto.

I claim:

1. A burner for liquid fuel, comprising a basin having a flat bottom and provided with an upstanding wall at the periphery of said bottom, said bottom having a centrally disposed air opening therethrough and an upstanding wall encircling said opening, said two upstanding walls forming between them an annular channel, an inlet for liquid fuel communicating with said channel, a cap having openings in its wall and covering said air inlet, said cap standing in said annular channel, an open topped silencer mounted on the top of the peripheral wall of said basin, the lower part of said silencer being cylindrical

and provided with air openings and the upper part being tapered inwardly above said cylindrical part to the opening in the top, a vertically movable support for said basin, cap and silencer, an enclosing cylindrical cover held in a fixed position and disposed in encircling relation to said basin, cap and silencer, a flat cover disposed on the top end of said cylindrical cover and having a central opening above said basin, cap and silencer, and means for imparting a reciprocatory motion to said basin, cap and silencer on their vertical support toward and from said flat cover thereby to regulate the flame.

15 2. A burner for liquid as set forth in claim 1, said support comprising a lever pivoted intermediate its length to a fixed support, the axis of said support being horizontally disposed whereby the ends of the lever may be swung upwardly and downwardly, a vertically extending clamp pivotally connected to one end of said lever, said clamp having at its upper end horizontally extending arms underlying said basin and thereby supporting the basin, cap and silencer, and means pivotally connected to the opposite end of said lever and operative to move the lever on its pivot thereby to reciprocate the basin, cap and silencer toward and from said fixed cover.

20 3. A burner for liquid fuel as set forth in claim 2, said lever-moving means comprising a threaded stem pivotally connected to the end of the lever opposite the clamp and a nut supported for rotation in a fixed vertical position and in engagement with the threaded portion of said stem.

MARIO NAVA.
